UNITED STATES PATENT OFFICE.

ADOLPH WAHLE, OF DAVENPORT, IOWA.

MECHANICAL MOVEMENT.

No. 892,338.

Specification of Letters Patent.

Patented June 30, 1908.

Application filed January 2, 1908. Serial No. 408,908.

To all whom it may concern:

Be it known that I, ADOLPH WAHLE, a citizen of the United States, and a resident of Davenport, in the county of Scott and State of Iowa, have invented certain new and useful Improvements in Mechanical Movements, of which the following is a clear, full, and exact description.

My invention relates to mechanical movements for use in washing machines, mangles, churning, and other machinery where it is desired to convert a continuous rotary motion of a drive-shaft into a rotary reciprocal motion of the driven-shaft.

The object of my invention is to utilize the force or momentum of a rapidly revolving fly-wheel to assist in moving the parts past the point of reversal or "dead-center", and thereby continue the operation of reversal with the expenditure of less energy on the part of the operator than would be required if the fly-wheel were dispensed with or not used. This I accomplish by the means hereinafter fully described and as more particularly pointed out in the claims.

In the drawings:—Figure 1 is a side elevation showing my invention applied, in this particular instance, to the top or cover portion of a laundry tub. Fig. 2 is a central vertical section taken through the vertical plane of the operating shafts. Fig. 3 is a top plan view of the same. Fig. 4 is a view similar to Fig. 3 having the gear casing removed to expose the parts below the same. Fig. 5 is a detail view of the inner end of the frame-work and the casing showing the manner of disposing the operating lever.

The supporting-frame for my improved mechanical movement consists of a base-plate 1, and a casing 2 removably mounted upon the same. At the outer end of the base-plate are located suitable horizontal bearings 3, in which a continuously revolute shaft 4 is journaled. This shaft is provided on its outer end with a balance-wheel 5, while on its inner end a small bevel-pinion 6 is mounted, that meshes with a bevel-gear 7 secured on a short vertical spindle 8 arising from the base-plate. The upwardly extending boss of bevel-gear 7 is provided with a small straight toothed pinion 9 that is fast thereon and rotates therewith. Mounted in vertical bearings in the base-plate, preferably in the same vertical plane with shaft 4, is a suitable rotary reciprocal shaft 10, that derives its motion from the continuously rev-

olute shaft 4, through the medium of suitable transforming mechanism that will hereinafter be described. A large gear 11 that has a downwardly elongated journaling sleeve 12, is loosely mounted on this rotary reciprocal shaft 10 in such manner, that, while it engages with pinion 9, and is rotated continuously thereby, its movement is independent of the reciprocal motion of said shaft. Pivoted to a stud projecting up from the top of bearing 3, at one end, is a horizontally reciprocal rack-lever 13, that extends over all of the before mentioned gearing, and has its free end resting upon the smooth upper face of gear 11. This lever is substantially T-shaped and is provided at the intersection of its branches with a cross-shaped opening, the transverse slot 14 of which is in the same transverse plane as, and is adapted to accommodate the passage therethrough of the rotary reciprocal shaft 10. The longitudinally disposed slot 15 of this opening affords a guide for a suitable roller-pin 16, that projects vertically from the upper face of gear 11. The slotted end of this lever extends under a pinion 17 fast on shaft 10, and the outer extremity thereof is provided with a segmental-rack 18 that engages said pinion 17 and turns the same and shaft 10 in a rotary reciprocal manner as it is moved from side to side on its pivot. A suitable arm 19 projects laterally from the back of rack 17, and extends through an opening in a vibratory operating or hand-lever 20, which latter is, preferably, provided with an enlarged ball-shaped head 21 on its lower end, that is adapted to be seated and journaled in a suitably shaped socket 22 cast integral with and arising from the inner end of the base-plate.

In order to provide a covering for the gears, the base-plate 2 is provided, between the two shafts, with an integral mutilated shell 23, that rises, preferably, to the height of the bevel-gear 7, which latter together with the bevel-pinion 6 is partially inclosed thereby. This shell is provided with lateral lugs 24, to which are secured suitable straddling feet 25 on the superimposed plate 2. Said plate at its inner end has a dome-shaped hood 26 that incloses the pinion 17 and has vertical bearings in its top for the rotary reciprocal shaft 10. A suitable elliptical or pear-shaped band 27 is so disposed around gear 11 and pinion 9 as to prevent articles from catching in the teeth and stopping the

gearing. Said band rests at its smaller end on the upper face of gear 7, while its outer or larger portion is provided with a transverse bracket 28 that is seated on the rim of the 5 socket 22. In addition to this protection the upper member 2 of the supporting-frame is provided on each side of the central dome 26 with upturned lips 29, that guard the face of the rack 18 on the reciprocal arm 13.

- 10 In operation, the operating lever 20 is reciprocated and moves the segmental rack 18 back and forth, which latter meshes with pinion 17 and causes a reciprocal rotating movement of the shaft 10. This back and 15 forth movement of the rack moves the roller pin 16 alternately from one end to the other of slot 15, thus imparting a rotating movement to the large gear 11, and the latter, through the medium of pinion 9, bevel-gear 7 20 and bevel-pinion 6, revolves the balance-wheel 5 at a high speed. The momentum of the balance-wheel keeps the gearing in motion and materially assists the operator in reciprocating lever 20, and particularly in carrying 25 the roller-pin 16 past the "dead-center" on gear 11, thus reducing the amount of power required to keep the device in motion to a minimum.

What I claim as new is:—

- 30 1. A mechanical movement comprising a suitable supporting frame, a rotary reciprocal shaft journaled therein, a gear loose on said shaft, a pinion secured to said shaft, a continuously revolute shaft, a pivoted segmental 35 rack engaging both said pinion and gear, and means for transmitting the motion of said rack through the medium of said gear to the last mentioned shaft.
- 40 2. A mechanical movement comprising a suitable supporting-frame, a rotary reciprocal shaft journaled therein, a gear loose on said shaft, a pinion secured to said shaft, a continuously revolute shaft, a vibratory arm pivoted at a distance from said reciprocal 45 shaft having a rack on its free end that engages said pinion, devices for rotating said gear independent of said reciprocal shaft, and means for transmitting the motion of said gear to said revolute shaft.
- 50 3. A mechanical movement comprising a suitable supporting-frame, a rotary reciprocal shaft journaled therein, a gear loose on said shaft, a pinion secured to said shaft, a continuously revolute shaft, a vibratory arm pivoted at a distance from said reciprocal shaft having a rack on its free end that engages said pinion, devices for rotating said gear independent of said reciprocal shaft, and intermediate 55 gearing for transmitting the motion of said gear to said revolute shaft.

- 60 4. A mechanical movement comprising a suitable supporting frame, a rotary reciprocal shaft journaled therein, a gear loose on said shaft having a stud projecting from its 65 face, a pinion secured to said shaft, a contin-

uously revolute shaft, a vibratory arm pivoted at a distance from said reciprocal shaft having a rack on its free end that engages said pinion, said arm also having a slot therein that engages said stud for rotating said gear independent of said reciprocal shaft, and means for transmitting the motion of said gear to said revolute shaft. 70

5. A mechanical movement comprising a suitable supporting-frame, a rotary reciprocal shaft journaled therein, a gear loose on said shaft, a pinion secured to said shaft, a continuously revolute shaft, a vibratory arm pivoted at a distance from said reciprocal shaft having a rack on its free end that engages said pinion, a pivoted hand-lever engaging the free end of said arm, devices for rotating said gear independent of said reciprocal shaft, and means for transmitting the motion of said gear to said revolute shaft. 75 80 85

6. In a mechanical movement a rotary reciprocal shaft, a pinion secured thereon, a gear loose on said shaft, a pivoted segmental rack engaging said pinion and provided with means for rotating said gear independent of said shaft, a continuously revolute shaft, means for transmitting the motion of said gear to said last mentioned shaft, and a divided supporting-frame in which said mechanism is mounted having integral members 90 95 that surround and inclose the same.

7. A mechanical movement comprising a suitable supporting-frame, a rotary reciprocal shaft journaled therein, a gear loose on said shaft, a pinion secured to said shaft, a continuously revolute shaft, a pinion thereon, an idle-gear engaging the same having an integral pinion on its upper face, engaged by said first mentioned gear, and a vibratory arm engaging the gear on said 100 105 rotary reciprocal shaft and provided with a segmental rack adapted to engage the fixed pinion on said shaft.

8. A mechanical movement comprising a suitable supporting-frame, a rotary reciprocal shaft journaled therein, a gear loose on said shaft having a stud projecting from its upper face, a pinion secured to said shaft above said gear, a continuously revolute shaft, a pinion thereon, an idle-gear engaging the same and having an integral pinion on its 110 115 upper face engaged by said first mentioned gear, and a vibratory arm having a longitudinal slot therein, in which said stud operates and provided with a segmental rack adapted 120 to operate the pinion on said rotary reciprocal shaft.

9. A mechanical movement comprising a suitable supporting-frame, a rotary reciprocal shaft journaled therein, a gear loose on said shaft having a stud projecting from its upper face, a pinion secured to said shaft above said gear, a continuously revolute shaft, a pinion thereon, an idle-gear engaging the same and having an integral pinion on its 125 130

upper face engaged by said first mentioned gear, a vibratory arm having a longitudinal slot therein in which said stud operates and provided with a segmental rack adapted to 5 operate the pinion on said rotary reciprocal shaft, and a pivoted operating lever engaging the outer free end of said arm.

10. A mechanical movement comprising a suitable supporting-frame, a rotary reciprocal shaft journaled therein, a gear loose on said shaft having a stud projecting from its upper face, a pinion secured to said shaft above said gear, a continuously revoluble shaft, a balance wheel on the outer end 15 thereof, a pinion thereon, an idle-gear engag-

ing the same and having an integral pinion on its upper face engaged by said first mentioned gear, a vibratory arm having a longitudinal slot therein in which said stud operates and provided with a segmental rack 20 adapted to operate the pinion on said rotary reciprocal shaft, and a pivoted operating lever engaging the outer free end of said arm.

In testimony whereof I have hereunto set my hand and seal this 9th day of December, 25 A. D., 1907.

ADOLPH WAHLE. [L. s.]
